APPARATUS FOR COOLING AIR BY THE
EVAPORATION OF LIQUIDS

Frank C. Simonds, Moylan, Pa.

Application March 21, 1947, Serial No. 736,247

6 Claims. (Cl. 62—152)

1

This invention relates to a cooling system, and more particularly a system for cooling a circulated fluid which carries heat from a heated article or chamber. The invention is especially useful in connection with air-cooling electro-magnetic apparatus used in turbo-electric-driven ships, to which use, however, it is not restricted.

One object of the invention is to prevent a secondary cooling fluid from entering a primary cooling fluid in a heat exchanger. A further object is the provision of a simple and efficient cooling system which may be effectively operated from available apparatus. Other objects and advantages of the invention will be apparent from the present specification.

The invention is shown by way of illustration in the accompanying drawings, in which—

Fig. 1 is a diagrammatic view of one form of the invention as used for cooling electro-magnetic apparatus;

Fig. 2 is a diagrammatic view of a slightly different form of the invention also applied to electro-magnetic apparatus;

Fig. 3 is a diagrammatic view of a different form of the invention applied to air conditioning apparatus; and

Fig. 4 is a diagrammatic view of still a different form of the invention, also applied to air conditioning apparatus.

Many installations exist in which a fluid is used to remove heat from a heating point and is then circulated through a cooler, where heat is removed therefrom, whence it is recirculated past the heating point. Cycles of this nature are common in air conditioning systems and on ships where weather may prevent employment of fresh air for cooling. Separate refrigerating plants for cooling the recirculated cooling fluid require expensive apparatus and a considerable consumption of power. Furthermore, leakage of the secondary cooling fluid, which cools the cooler, into the primary cooling fluid, which is circulated through the cooler to give up its heat therein, may produce undesirable results. For example, where air is used to cool electro-magnetic apparatus as the motors and generators of turbo-electric-driven ships, the heated air coming from the housings of such electro-magnetic units customarily passes through an air cooler having water tubes through which sea water is pumped. Corrosion of these water tubes by the sea water results in leakage thereof into the cooled air and deposit of moisture and salt on the electro-magnetic parts. Such deposits may clog, corrode or even burn out the electrical apparatus.

2

I have found that, where power units which employ condensers are available, it is possible to cool the primary cooling fluid without employing expensive apparatus, and without large consumption of power; and I have found it possible at the same time to avoid leakage of the secondary into the primary cooling fluid. Essentially, the vacuum of a vacuum condenser is applied to a heat exchanger to cool the primary cooling fluid which is recirculated past the heating point and through the heat exchanger.

The embodiment of the invention shown in Fig. 1 illustrates the application of the invention to an air-cooling system for electro-magnetic apparatus, as a motor or generator of a turbo-electric-driven ship. This illustration includes an electro-magnetic apparatus 10 (which may be a motor or a generator) the casing of which comprises a sealed chamber containing the parts to be cooled. A closed conduit system is connected across the chamber. Thus, a heated air conduit 11 connects the apparatus 10 to a primary cooling fluid passage 12 in a heat exchanger 13, and a cooled air conduit 14 connects the primary cooling fluid passage again to the apparatus. The air, or primary cooling fluid may be circulated through the apparatus in any known or convenient manner, as by a fan (not shown) in the casing of the electro-magnetic apparatus. If the heat exchanger is properly cooled, therefore, heat will be abstracted from the air brought thereto by the heated air conduit 11, and the cooled air will be carried therefrom to the electro-magnetic apparatus by the cooled air conduit 14.

The heat exchanger 13 is cooled by evaporating a liquid therein. Thus, the heat exchanger has a secondary cooling fluid passage sealed from and in heat exchanging relationship with the primary cooling fluid passage 12. In the embodiment illustrated, the secondary cooling fluid passage comprises a water box or receiving header 15, a vacuum chamber or discharge header 16, and a number of tubes 17 extending across the primary cooling fluid passage 12 and connecting the headers 15 and 16. A secondary cooling fluid, passing across the primary cooling fluid passage 12 through the tubes 17, will therefore abstract heat from the primary cooling fluid, if the temperature of the former is lower than that of the latter.

The temperature of the secondary cooling fluid in the heat exchanger is maintained at a relatively low point by the action of a condenser

18, with which it is connected, the action of which will now be described.

The condenser employed in the present apparatus may be the main condenser of a steam-operated prime mover, as that of a turbo-electric-driven ship. The condenser 18 receives the exhaust steam of one or more units through an exhaust pipe 19 and a connecting pipe 20, in well-known manner. Condensate formed in the condenser is forced by a pump 21 into the usual 10 feed-water line 22.

The condenser 18 is connected to the heat exchanger through a closed pipe system which includes the secondary cooling fluid passage (headers and tubes) of the heat exchanger. Thus, a 15 pipe 23 is connected, as at 24, to the feed water line 22 adjacent the pump 21, and is connected at its other end to the receiving header 15 in the heat exchanger. A valve 25 in the pipe 23, adjacent its connection with the feed water line, 20 permits condensate from the condenser, under pressure of the pump 21, to enter the pipe 23 or excludes the condensate therefrom. The closed pipe system through the condenser and the heat exchanger is completed by a pipe 26, 25 coupled to the discharge header 16 of the heat exchanger, and joined to an extension pipe 27, which is in turn connected to a feed pipe 28 coupled to the condenser. A valve 29 controls the flow through the extension pipe 27, and a 30 valve 30 in the feed pipe 28 permits or prevents fluid therein from entering the condenser 18.

Operation of the apparatus so far described will be readily understood. The valves 25, 29 and 30 being open, condensate from the condenser 18 enters the pipe 23 under pressure of the pump 21 and is sprayed into the water box or receiving header 15 of the heat exchanger 13. At the same time, vacuum from the condenser is applied to the vacuum chamber or discharge header 16 of the heat exchanger from the condenser 18 through the feed pipe 28, the extension pipe 27 and the pipe 26. Accordingly, the condensate sprayed into the receiving header is boiled or evaporated, passes through the tubes 17 to the vacuum chamber or discharge header whence it returns to the condenser as water vapor. As the condensate boils or evaporates under the vacuum of the condenser, it absorbs its heat of vaporization from the heat exchanger and the air or primary cooling fluid circulated therethrough, thereby cooling the air or primary cooling fluid.

Without wishing to be limited to any quantitative statements, and without asserting the complete accuracy thereof, the following will give an idea of the cooling action of the apparatus. The condenser may be considered as being under a vacuum of 28 inches of mercury and at a temperature of 100 degrees Fahrenheit. The condensate in the condenser, having given up its latent heat of condensation to the cooling water of the condenser, and being unable to regain it because of the continued removal of heat by the cooling water, remains in liquid form in the condenser. Furthermore, the pump 21 delivers the condensate to the heat exchanger at substantially 100 degrees Fahrenheit. Here, again, subjected to the vacuum of the condenser, the condensate is able to gain its latent heat of vaporization from the primary cooling fluid passing through the heat exchanger. Thereupon the condensate evaporates and becomes vapor at 100 degrees Fahrenheit, in which form it returns to the condenser. Cooling air, leaving the electro-magnetic apparatus at, say 130 degrees Fahrenheit may

therefore be cooled in the heat exchanger to 100 degrees Fahrenheit.

If it is desired to reduce the temperature of the primary cooling fluid still further as it passes through the heat exchanger, one way of doing so is to apply a refrigerating coil 31 to the pipe 23 between the pump 21 and the receiving header 15.

Another means for reducing still further the temperature of the primary cooling fluid is illustrated in Fig. 1. The pipe 26 which is coupled to the discharge header 16 is shown as continued beyond the point at which it is joined to the extension pipe 27 to connect with an ejector 32. A valve 33 serves to permit or shut off flow through the pipe 26 to the ejector. The ejector is operated in well-known manner by steam from a pipe 34, and discharges into the condenser through the feed pipe 28. A valve 35 serves to shut off the ejector. Thus, with the extension pipe shut off by the valve 29 and the valves 33 and 35 open, the ejector will apply vacuum to the header 16 in addition to that of the condenser. It has been found that an additional inch of vacuum may be applied by the ejector to the secondary cooling fluid passage through the heat exchanger. Thus the ejector 32 may bring the vacuum in the heat exchanger down to 29 inches of mercury; and the resultant boiling or evaporation of the condensate therein will reduce its temperature to substantially 80 degrees Fahrenheit. Consequently if air at 130 degrees Fahrenheit enters the heat exchanger from the electro-magnetic apparatus 10, the condensate will absorb its heat of vaporization therefrom; and it has been found possible to reduce the temperature of the cooled air from 130 degrees to 90 degrees Fahrenheit in the heat exchanger.

In this connection it is to be noted that only a small part of the condensate from the condenser is used in the heat exchanger 13. Furthermore, the condensate coming from the condenser 18 is fresh water and does not tend to corrode the tubes 17 in the heat exchanger or to enter the primary cooling fluid.

In the embodiment of the invention which is illustrated in Fig. 2 a slightly different form of the invention is shown wherein the ejector 32 is continually used to apply a vacuum to the heat exchanger 13. Furthermore, the ejector discharges into the condenser through an inter-cooler 36, through which the feed water line 22 passes in a coil 37. Thus the heated vapor from the heat exchanger 13 filling the inter-cooler 36 on its way to the condenser 18 gives up some of its heat to the feed water. A pipe 38 carries the condensate from the inter-cooler to the condenser.

In Fig. 3 the invention is shown in its application to an air conditioning system which is located at a distance from the cooling machinery. Here a column of heated air is cooled by a primary cooling fluid which is circulated through the air column and through a heat exchanger, where it is cooled. The heat exchanger is cooled by boiling or evaporation under the vacuum of the usual condenser 18 and the vacuum induced by air ejector 32a.

As illustrated in Fig. 3, the heated air to be cooled is carried by an intake conduit 39 into a casing 40 which it leaves by a discharge conduit 41. The primary cooling fluid is circulated through the casing in a coil 42, which is connected by a supply conduit 43a and a return conduit 44a with a heat exchanger 13a where the primary

cooling fluid is cooled. A primary cooling fluid pump 43 circulates the primary cooling fluid between the casing 40 and the heat exchanger 13^a.

Because the primary cooling fluid functions at a distance from the heat exchanger, water is used as the primary cooling fluid. For a given pipe diameter water will carry a larger number of B. t. u.'s than air.

The heat exchanger 13^a is of a different type from the heat exchanger 13 which has been described. The heat exchanger 13^a is an ordinary tank into which the heated primary cooling fluid is carried by the return conduit 11^a and from which the cooled primary cooling fluid is carried by the supply conduit 14^a. To cool the heat exchanger 13^a, condensate from the condenser 18 is carried from the feed water line 22^a into the tank by a make up water pipe 23^a having a valve 25^a therein; and the vacuum of the condenser 18 augmented by the vacuum induced by the ejector 32^a is applied to the top of the tank by a pipe 26^a. The primary and secondary cooling fluids are commingled in this heat exchanger.

Thus, cooling liquid at the temperature of the condenser is fed into the heat exchanger and the vacuum of the condenser plus the induced vacuum of the ejector boils or evaporates the contents of the tank whereby the entire body of liquid is cooled. Heated cooling liquid from the return conduit 11^a is therefore cooled by the body of water with which it mixes in the tank. Cooled water from the body of water in the tank is withdrawn by the primary cooling fluid pump 43 and sent through the supply conduit 14^a into the coil 42.

In this apparatus which has just been described, the cooling process is, broadly viewed, the same as those disclosed in Figs. 1 and 2. The heated cooling fluid is passed through a heat exchanger which is cooled by evaporation of a liquid therein.

Fig. 4 shows an application of the invention to an air conditioning system which is located nearer to the cooling machinery than that illustrated in Fig. 3. In this embodiment the air which is being conditioned is passed through a heat exchanger 13^b which is very similar to the heat exchanger 13 shown in Figs. 1 and 2. The heat exchanger is vacuum-cooled as is that shown in Figs. 1 and 2.

In the embodiment shown in Fig. 4, the heat exchanger 13^b has an air passage 12 therein to which a warm air pipe 44 carries air to be cooled. A cool air pipe 45 carries the cooled air from the heat exchanger 13^b.

The heat exchanger 13^b is constructed and operated like the heat exchanger 13 shown in Figs. 1 and 2. Thus a passage like the secondary cooling fluid passage in the previously described heat exchanger is provided in the heat exchanger 13^b and is sealed from and in heat exchange relationship with the air passage 12 therein. This passage comprises a water box or receiving header 15, a vacuum chamber or discharge header 16, and a number of tubes 17 extending across the air passage 12 and connecting the headers 15 and 16.

The heat exchanger is connected to the condenser 18 in the same manner as has been described in connection with the heat exchanger shown in Fig. 1. Thus a pipe 23^b is connected as at 24^b to the feed water line 22^a adjacent the pump 21, and is connected at its other end to the receiving header 15. A valve 25^b in the pipe 23^b permits condensate from the condenser, under

pressure of the pump 21, to pass through the pipe 23^b, or prevents its passage therethrough. A pipe 26^c coupled to the discharge header 16 connects the heat exchanger to an ejector 32^b similar to that shown in the previously described embodiments of the invention. A valve 33^b serves to permit or shut off flow through the pipe 26^c to the ejector. The ejector is operated by steam from a pipe 34^b, controlled by a valve 35^b, and discharges into the condenser 18 through a pipe 28^c. The heat exchanger 13^b is cooled in the manner which has already been described in connection with the similar heat exchangers.

The heat exchanger 13^b may be easily adapted to warming instead of cooling the air which passes through the air passage 12 therein. Accordingly, a steam pipe 46, controlled by a valve 47 may serve to admit steam to the receiving header 15, and traps 48 and 49 may be connected to the bottoms 10 of the headers 15 and 16 respectively. When the air is being warmed the valves 25^b, 33^b and 35^b in the cooling system are, of course, closed.

From the foregoing it will be apparent that the invention provides a simple and efficient cooling system which may be effectively operated from an available condenser or ejector, or both. Furthermore, secondary cooling fluid, which is under vacuum, cannot enter the primary cooling fluid, and since the secondary cooling fluid is fresh water it will not corrode the pipes of the heat exchanger.

The particular forms of the invention here described and illustrated in the accompanying drawings are presented merely as examples of how 35 the invention may be applied. Other forms, embodiments and applications of the invention, coming within the proper scope of the appended claims, will readily suggest themselves to those skilled in the art.

40 I claim:

1. In apparatus for cooling a fluid, a heat exchanger having primary and secondary cooling fluid passages therein in fluid sealed and heat exchange relationship with respect to each 45 other, a primary cooling fluid conduit system connected to said primary cooling fluid passages of the heat exchanger, an exhaust steam line, a condenser operating under vacuum and connected to said exhaust steam line to receive steam therefrom and condense the same, a pipe system for introducing at least a portion of said condensate from said condenser into one end of the secondary cooling fluid passages of said heat exchanger, and a second pipe system connecting the vacuum side 55 of said condenser to the other end of said secondary fluid passages of the heat exchanger to reduce the pressure therein and vaporize the condensate thereby cooling the primary cooling fluid passing through said heat exchanger.

60 2. In apparatus for cooling a fluid, a heat exchanger having primary and secondary cooling fluid passages therein in fluid sealed and heat exchanging relationship with respect to each other, a primary cooling fluid conduit system 65 connected to said primary cooling fluid passages of the heat exchanger, an exhaust steam line, a condenser operating under vacuum and connected to said exhaust steam line to receive steam therefrom and condense the same, a pipe system for introducing at least a portion of said condensate from said condenser into one end of the secondary cooling fluid passages of said heat exchanger, a second pipe system connecting the vacuum side of said condenser to the other end 70 75 of said secondary fluid passages of the heat ex-

changer to reduce the pressure therein and vaporize the condensate introduced therein thereby cooling the primary cooling fluid passing through said heat exchanger, and an ejector connected in said second pipe system and operated by a steam line connected thereto to further increase the vacuum in said heat exchanger.

3. In apparatus for cooling a fluid, a heat exchanger having primary and secondary cooling fluid passages therein in fluid sealed and heat exchanging relationship with respect to each other, a primary cooling fluid conduit system connected to and including said primary cooling fluid passages of the heat exchanger, an exhaust steam line, a condenser operating under vacuum and connected to said exhaust steam line to receive steam therefrom and condense the same, a pipe system to introduce a predetermined portion of said condensate from said condenser under positive pressure into one end of the secondary cooling fluid passages of said heat exchanger, a second pipe system connecting the vacuum side of said condenser to the other end of said secondary fluid passages of the heat exchanger to reduce the pressure therein and vaporize the condensate thereby cooling the primary cooling fluid passing through said heat exchanger, an ejector connected in said second pipe system and operated by a steam line connected thereto to further increase the vacuum in said heat exchanger, and means selectively operable at will to cut said ejector in and out of said second pipe system as desired.

4. In apparatus for cooling a fluid, a heat exchanger having primary and secondary cooling fluid passages therein in fluid sealed and heat exchanging relationship with respect to each other, a primary cooling fluid conduit system connected to and including said primary cooling fluid passages of the heat exchanger, an exhaust steam line, a condenser operating under vacuum and connected to said exhaust steam line to receive steam therefrom and condense the same, a pipe system including a pump operable to introduce a predetermined portion of said condensate from said condenser under positive pressure into one end of the secondary cooling fluid passages of said heat exchanger, means to regulate and control the amount of condensate introduced into said heat exchanger, and a second pipe system connecting the vacuum side of said condenser to the other end of said secondary fluid passages of the heat exchanger to reduce the pressure therein and vaporize the condensate thereby cooling the primary cooling fluid passing through said heat exchanger.

5. In apparatus for cooling a fluid, a heat exchanger having primary and secondary cooling fluid passages therein in fluid sealed and heat exchanging relationship with respect to each other, a primary cooling fluid conduit system connected to and including said primary cooling

fluid passages of the heat exchanger, an exhaust steam line, a condenser operating under vacuum and connected to said exhaust steam line to receive steam therefrom and condense the same, a pipe system including a pump operable to introduce a predetermined portion of said condensate from said condenser under positive pressure into one end of the secondary cooling fluid passages of said heat exchanger, means to regulate and control the amount of condensate introduced into said heat exchanger, a second pipe system connecting the vacuum side of said condenser to the other end of said secondary fluid passages of the heat exchanger to reduce the pressure therein and vaporize the condensate thereby cooling the primary cooling fluid passing through said heat exchanger, and an ejector connected in said second pipe system and operated by a steam line connected thereto to further increase the vacuum in said heat exchanger.

6. In apparatus for cooling a fluid, a heat exchanger having primary and secondary cooling fluid passages therein in fluid sealed and heat exchanging relationship with respect to each other, a primary cooling fluid conduit system connected to and including said primary cooling fluid passages of the heat exchanger, an exhaust steam line, a condenser operating under vacuum and connected to said exhaust steam line to receive steam therefrom and condense the same, a pipe system including a pump operable to introduce a predetermined portion of said condensate from said condenser under positive pressure into one end of the secondary cooling fluid passages of said heat exchanger, means to regulate and control the amount of condensate introduced into said heat exchanger, a second pipe system connecting the vacuum side of said condenser to the other end of said secondary fluid passages of the heat exchanger to reduce the pressure therein and vaporize the condensate thereby cooling the primary cooling fluid passing through said heat exchanger, an ejector connected in said second pipe system and operated by a steam line connected thereto to further increase the vacuum in said heat exchanger, and means selectively operable at will to cut said ejector in and out of said second pipe system as desired.
